DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

Continuation of abandoned application Ser. No. 391,291,
Aug. 27, 1973. This application Dec. 9, 1974, Ser. No.
531,008

Int. Cl. G06f 15/46
U.S. Cl. 444—1

In a data processing system, a complex article, e.g. an integrated circuit may be identified by the system as an economically acceptable article after partial or less than one hundred percent testing by the steps of: (a) storing topological data or geometry of each physical element for embodying a logical net in an integrated circuit; (b) storing test simulation results of each logical state in the logical nets embodied in the integrated circuit; (c) identifying fault sensitive geometry in all logical elements and nets that perform and interact in achieving a design function for the integrated circuit; (d) identifying geometry for the logical elements and net for which no test simulation could be determined; (e) tabulating the sensitive areas of untested geometries; (f) calculating fault occurrence rates for the sensitive geometries; (g) adjusting the fault occurrence rates for the sensitive geometries for (1) production experience and (2) clustered distribution of faults instead of uniform distribution of faults, and (h) projecting (1) the yield of tested articles and (2) the quantity of defective articles shipped when full or one hundred percent testing is not applied to the articles.
